The ornamental design for a resuscitation bag, as shown and described.

DESCRIPTION

FIG. 1 is a perspective view of a resuscitation bag showing our new design made of a textured, translucent material;

FIG. 2 is a front elevation view thereof;

FIG. 3 is a rear elevation view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a cross-sectional view thereof taken along the line 8-8 of FIG. 7;

FIG. 9 is a perspective view of a second embodiment of our claimed design, the difference consisting of the resuscitation bag being made of a textured, opaque material;

FIG. 10 is a front elevation view thereof;

FIG. 11 is a rear elevation view thereof;

FIG. 12 is a right side elevational view thereof;

FIG. 13 is a left side elevational view thereof;

FIG. 14 is a top plan view thereof; and,

FIG. 15 is a bottom plan view thereof.

1 Claim, 15 Drawing Sheets(56)
